STEAM GENERATING SYSTEM

John Phillips Badenhausen, Philadelphia, Pa.

Application December 22, 1943, Serial No. 515,245

4 Claims. (Cl. 122—1)

This invention relates to steam generating systems.

In the operation of steam power plants, particularly of the sizes and with the pressures employed in central stations, difficulties have been encountered because of the presence of solid materials. The difficulties have taken various forms. For example, the presence of such materials has caused unexpected tube failures at high operating temperature ranges. Improvement in the character of circulation of the liquid in the boiler furnished only a partial solution. Certain solids carried over from the boiler and deposited on the governor valves, on reducing valves and on the turbine blading and nozzles.

Analysis of the deposits on turbine blading indicated that the chief constituents were sodium hydroxide and sodium silica although other boiler water salts were also found to be present. The deposits did not reflect the same percentage of materials as those found in the boiler water.

Such deposits of solids in the turbine have been known to decrease the output capacity by more than a quarter in a month's time. Various efforts have been made to remedy this situation. Washing of the steam with feedwater has been tried with indifferent success. Changes have been suggested in the feedwater treatment but these have not produced any very marked improvement.

In a steam generating system where the quantities of steam are large and of the order of a million pounds of steam in from one to ten hours, even a relatively small quantity of solid material continuously introduced has a cumulative effect which may quickly become troublesome.

In accordance with the present invention provision is made for the continuous generation of steam free from objectionable solids content.

In accordance with the present invention, provision is made for segregating the extraneous solid materials in a simple manner, so that the same may be readily removed as desired.

In accordance with the present invention also, provision is made for continuous operation of high capacity steam generators and without the necessity for complete shutdown for cleaning to remove solid materials in the water.

Other advantages of the invention will be apparent from the annexed specification and claims.

The nature and characteristic features of the invention will be more readily understood from the following description, taken in connection

with the accompanying drawing forming part hereof, in which:

Figure 1 is a diagrammatic view illustrating the invention.

Fig. 2 is a vertical central sectional view through a portion of the apparatus, and taken approximately on the line 2—2 of Fig. 3.

Fig. 3 is a horizontal sectional view taken approximately on the line 3—3 of Fig. 2, and

Fig. 4 is a fragmentary vertical sectional view taken approximately on the line 4—4 of Fig. 3.

It will, of course, be understood that the description and drawing herein are illustrative merely, and that various modifications and changes may be made in the structure disclosed without departing from the spirit of the invention.

Referring more particularly to the drawing, a steam generator 10 having a superheater 11 is illustrated diagrammatically, and is preferably provided with a pair of precipitator units 12, shown in detail in Figs. 2, 3 and 4. The steam generator 10 is preferably for central station operation and with a high capacity of steam generation of the order of 100,000 to 1,000,000 lbs. steam per hour.

The precipitators 12 are preferably provided in pairs so that one may be operated and one may be off the line as hereinafter pointed out.

Each of the precipitators 12, in accordance with the present invention, is of much smaller size than the steam generator 10, and each is of a capacity sufficient to provide the requisite make up for the system. Each of the precipitators preferably has a top wall 15, a bottom wall 16, a front wall 17, a rear wall 18, and spaced side walls 19. At the rear wall 18 a plurality of vertical headers 20 is provided, spaced along the rear wall 18, the number of headers 20 being determined by the required output capacity of the precipitators. The vertical headers 20 are each terminated near the bottom wall 16, and their upper ends preferably extend above the top wall 15 for purposes presently to be explained.

The vertical headers 20 may, if desired, be provided with suitable positive circulators (not shown) as illustrated in my prior Letters Patent for Steam generators, No. 2,320,503.

A horizontal header 21 is provided at the upper portion of the front wall 17.

Banks of spaced steam generating tubes 22 are provided extending forwardly from lower portions of the rear vertical headers 20 to the front horizontal header 21, the tubes 22 of this bank

including horizontal portions and inclined portions 22a at their front ends.

Other banks of spaced steam generating tubes 23 are provided also, generally similar in shape to the tubes of banks 22, but at a higher level.

Upper banks of spaced steam generating tubes 24 are provided extending rearwardly from the front horizontal header 21 to the rear headers 20, and beneath the top wall 15.

The front wall 17 is illustrated as provided with a plurality of burner openings 25, although it will of course be understood that the invention is not restricted to firing in this manner.

To the rear of the front wall 17 an upwardly extending wall or baffle 30 is provided, preferably extending from the bottom wall or floor 16 to the lowermost tubes of the banks of tubes 24, and so that gases may pass over the top thereof. The space between the front wall 17, and the wall 30, and above the bottom wall 16, serves as a combustion chamber or as a chamber for the introduction of hot gases from some other source.

In the space between the rear wall 18 and the wall 30 a downwardly extending wall or baffle 31 is provided, preferably extending from the top wall 15 to the lowermost tubes of the banks of tubes 23. A plurality of passes are thus provided for the hot gases for contact with the tubes of the banks of tubes 22, 23 and 24.

The rear headers 20 are preferably connected by a suitable pipe 35 for the delivery of steam from the precipitators 12 and for the mixing thereof with the steam from the main steam generator 10 prior to the passage thereof through the superheater 11.

In the use of the apparatus of the present invention the steam generator 10 is operated in the customary manner for the generation of steam as required, but does not have any make up delivered thereto as heretofore. One of the precipitators 12 is operated to generate steam. The hot gases of combustion generated or available in the forward chamber pass upwardly and rearwardly in contact with the front portions of the tubes of the banks of the tubes 22, 23 and 24, over the top portion of the wall 30, then downwardly and rearwardly over the intermediate portions of the tubes of the banks of tubes 22, 23 and 24 beneath the baffle 31, then upwardly and rearwardly in contact with the rear portions of the tubes of the banks of tubes 22, 23 and 24, and then to the stack (not shown).

The steam generated in the tubes of the banks of tubes 22, 23 and 24 is delivered to the rear headers 20 for discharge.

The precipitator 12 is supplied with water in accordance with the make up requirements. The precipitator 12 is operated at the same pressure as the main steam generator 10, and steam only is delivered therefrom. The water with its contaminating solids, is retained in the precipitator 12 and is not delivered in liquid form to the steam generator 10. This permits of the collecting on the walls of the tubes of the banks of tubes 22, 23 and 24 of solid incrustations and also segregates the solids in the water in the precipitator 12. In this manner the solids are not delivered to the steam generator 10 and are also not delivered into the steam main. When and as desired the precipitator 12 which has been operating is taken off the line and the other precipitator 12 is used. The first precipitator 12 may then be

cleaned and the separated and segregated solids are removed in solid form as incrustations in the tubes 22, 23 and 24 and in dissolved form in the water in the tubes of the precipitator 12. After 5 the second precipitator 12 has similarly been operated the first precipitator 12 may again be substituted therefor.

In this manner the solids are kept under control and in selected locations, for removal from time to time as desired and without contamination of the main steam supply.

I claim:

1. In a steam generator, a rear wall, a top wall, a front wall providing the forward boundary of a combustion space, a baffle parallel to said front wall and providing the rear boundary of said combustion space, a front horizontal header at the upper part of said front wall, rear vertically disposed headers spaced along said rear wall, a bank of tubes connecting each of said rear headers to said front header, banks of substantially horizontal tubes extending from said front header to said rear headers adjacent said top wall, and a baffle to the rear of said first baffle for providing a plurality of passes of combustion gases in contact with said tubes.

2. In a steam generator, a rear wall, a top wall, a front wall providing the forward boundary of a combustion space, an upwardly extending baffle 30 parallel to said front wall, and providing the rear boundary of said combustion space, a front horizontal header at the upper part of said front wall, rear vertically disposed headers spaced along said rear wall, a bank of tubes connecting each of said rear headers to said front header and having horizontal portions and upwardly inclined front portions, banks of substantially horizontal tubes extending from said front header to said rear headers adjacent said top wall, and a downwardly extending baffle to the rear of said first baffle for providing a plurality of passes for the combustion gases in contact with said tubes.

3. In a steam generator, a rear wall, a top wall, a front wall providing the forward boundary of a combustion space, a baffle parallel to said front wall, a front horizontal header at the upper part of said front wall, rear vertically disposed headers spaced along said rear wall, a bank of tubes connecting each of said rear headers to said front header, the tubes of each bank having horizontal portions and upwardly inclined front portions, banks of substantially horizontal tubes extending from said front header to said rear headers adjacent said top wall, and a baffle to the rear of said first baffle for providing a plurality of passes for the combustion gases in contact with said tubes.

4. In a steam generator, a rear wall, a top wall, a front wall providing the forward boundary of a combustion space and having fuel inlet means, a front horizontal header at the upper part of said front wall, rear vertically disposed headers spaced along said rear wall, a bank of tubes connecting each of said rear headers to said front header, the tubes of said bank having horizontal portions and upwardly inclined front portions, banks of substantially horizontal tubes extending from said front header to said rear header adjacent said top wall, and a plurality of parallel baffles for providing a plurality of passes for the combustion gases in contact with said tubes.

JOHN PHILLIPS BADENHAUSEN.
